UNITED STATES PATENT OFFICE

109,076

DESIGN FOR A SPOON OR SIMILAR ARTICLE

Pierre J. Chéron, Stratford, Conn., assignor to Blackstone Silver Company, Stratford, Conn., a corporation of Illinois

Application January 29, 1938, Serial No. 74,709

Term of patent 14 years

To all whom it may concern:

Be it known that I, Pierre J. Chéron, a citizen of the United States, residing at Stratford, in the county of Fairfield and State of Connecticut, have invented a new, original, and ornamental Design for a Spoon or Similar Article, of which the following is a specification, reference being had to the accompanying drawing, forming a part thereof.

Fig. 1 is a front elevational view of a spoon or similar article, showing my new design.

Fig. 2 is a rear elevational view and;

Fig. 3 is a side elevational view of my new design.

I claim:

The ornamental design for a spoon or similar article as shown.

PIERRE J. CHÉRON.
